UNITED STATES PATENT OFFICE.

GEORGE B. THOMAS, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

ELECTRICAL RECEPTACLE.

1,145,717.

Specification of Letters Patent.

Patented July 6, 1915.

Application filed December 21, 1914. Serial No. 878,338.

To all whom it may concern:

Be it known that I, GEORGE B. THOMAS, a citizen of the United States of America, and residing at Bridgeport, in the county of 5 Fairfield and State of Connecticut, have invented a certain new and useful Improvement in Electrical Receptacles, of which the following is a specification.

My invention relates to electrical receptacles and particularly to lamp grips and the object of my invention is to provide a lamp receptacle with novel and inexpensive means for gripping an inserted lamp base or the like to prevent the same from "backing out" of the receptacle under the influence of vibration.

In the accompanying drawings, Figure 1 is a sectional elevation of a lamp socket in which my invention is embodied in one 20 form; Fig. 2 is a side elevation at right angles thereto; and Fig. 3 is a plan view of a receptacle.

In the form here shown the frictional grip upon the plug or base 8 is obtained by 25 means of tongues 5, formed at one or more places in the usual screw shell terminal 6 of the socket and engaged by relatively heavy steel plate springs 7 which bear constantly against the free ends of the tongues 30 5 and deflect the same inwardly into the path of the entering base of the lamp or the like. While it is not necessary that the tongues 5 should be formed with their free ends directed toward the bottom of the shell, 35 as shown, I prefer this construction, and in any event it is highly desirable that the shell be maintained in its complete annular form at its outer or receiving end so that the threads 9 therein remain undeformed and 40 thus insure a proper engagement with the threads of the entering base 8. The particular form of the springs which press these tongues 5 may be varied in many ways. That shown is perhaps the simplest form, 45 comprising a strap of spring steel bent at its lower end to form a base 10 perforated to receive the securing screw 11 which passes up through the body 12 of the receptacle and takes into the threaded yoke 13, overlying the base flanges 14 of the shell 6 in well known manner. The free end of the 50 spring 7 is sufficiently inclined inward to press the tongue 5 out of its normal position

so that it lies in the path of the entering plug or base.

The operation of the grip is obvious. As 55 the lamp is screwed home within the receptacle, the base 8 engages the tongues 5 and as it enters farther into the receptacle forces the tongues outward against the pressure of 60 the springs 7. The latter thus constantly press the tongues into a firm frictional grip 65 against the lamp base and prevent the latter from working loose under the influence of vibration. The number of the tongues 5 70 may be varied to suit the needs of the particular installation. Ordinarily two are sufficient. The use of two, as shown, is particularly convenient, inasmuch as it requires no change in the usual body construction of the socket, since the standard construction employs two securing screws 11 and these may be conveniently used to hold the two springs 7 in position. It is also a 75 relatively simple matter to form the tongues in the screw shell 6, since the screw shell is otherwise standard and it is merely necessary to form a U-cut in the shell at the point at which it is desired to locate the tongues. In the construction shown these 80 cuts are made above the base flanges 14 of the shell.

I claim as my invention:—

1. A lamp receptacle having a threaded shell side contact complete at its receiving 85 end but having a tongue formed in the side thereof, together with a relatively heavy spring normally deflecting the free end of the said tongue inward and into the path of an entering lamp base or the like to frictionally grip and hold the latter against 90 accidental rotary displacement.

2. A lamp receptacle having a threaded shell side contact complete at its receiving end, a securing screw for holding said shell 95 in position on the receptacle body, a tongue formed in the side of said shell with its free end alined with said securing screw, in combination with a relatively heavy plate spring engaged by said securing screw and 100 bearing against the free end of said tongue to deflect the latter inwardly into the path of an entering lamp base to frictionally grip and hold the latter against accidental rotary displacement.

3. A lamp receptacle having a threaded

shell side contact complete at its receiving end and provided with base flanges at its opposite end, a pair of securing screws passing through said base flanges, tongues formed on opposite sides of said shell contact above said base flanges, in combination with relatively heavy springs held by said securing screws and bearing against the free ends of said tongues and serving to 10 deflect the latter inward into the path of

an entering lamp base or the like to frictionally grip and hold the latter against accidental rotary displacement.

In testimony whereof I have signed my name to this specification, in the presence 15 of two subscribing witnesses.

GEORGE B. THOMAS.
